FEED, TAKE-UP, AND STRIPPER MECHANISM FOR ENCAPSULATING MACHINES

Charles C. Alvord, Worcester, Mass., assignor to Norton Company, Worcester, Mass., a corporation of Massachusetts

Application August 8, 1950, Serial No. 178,335

12 Claims. (Cl. 18—1)

1

The invention relates to a feed, take-up and stripper mechanism for encapsulating machines. One object of the invention is to provide a reliable stripper mechanism to remove capsules from the network of gelatin from which they were formed. Another object of the invention is to provide a simple and practical mechanism of the type indicated. Another object of the invention is to provide a stripper mechanism which can be readily opened up for threading the machine. Another object of the invention is to provide an easily adjustable stripper mechanism and one which can be quickly opened up for threading the machine. Another object of the invention is to provide, in an encapsulating machine, feed rolls and take-up rolls moving intermittently and a stripper mechanism advantageously timed to such intermittent motion.

Other objects will be in part obvious or in part pointed out hereinafter.

In the accompanying drawings illustrating one of many possible embodiments of the mechanical features of this invention:

Figure 1 is a front elevation of a portion of an encapsulating machine illustrating the feed rolls, take-up rolls and stripper mechanism;

Figure 2 is a rear elevation of a portion of the encapsulating machine showing the driving motor and part of the driving transmission;

Figure 3 is a horizontal sectional view on an enlarged scale taken on the line 3—3 of Figure 1;

Figure 4 is an elevation on a larger scale than that of Figure 2 of more of the transmission;

Figure 5 is a horizontal sectional view taken on the line 5—5 of Figure 1;

Figure 6 is a vertical sectional view on an enlarged scale taken on the line 6—6 of Figure 5;

Figure 7 is a vertical sectional view taken on the line 7—7 of Figure 3;

Figure 8 is a vertical sectional view taken on the line 8—8 of Figure 7 showing the details of the stripper;

Figure 9 is a vertical sectional view taken on the line 9—9 of Figure 1;

Figure 10 is an elevation of the stripper mechanism in open position.

The frame of the encapsulating machine includes a platform 20 to which is secured an upstanding panel 21. Referring now to Figure 2, supported by the platform 20 and suitably secured in place is an electric motor 22 having reduction gearing in a casing 23. The output shaft 24 of the gearing in the casing 23 has secured thereto a gear 25 which meshes with a gear 26 on a shaft 27 which extends into a casing 28 se-

5 cured to the platform 20. In the casing 28 is reduction gearing, not shown, such as a worm on the shaft 27 and a worm wheel on an output shaft 31 to which is secured a sprocket 32 driving a chain 33 which drives a sprocket 34 secured to a shaft 35 rotatably mounted in bearings 36 in a bracket 37 secured to the platform 20.

10 Referring now to Figure 4, also secured to the shaft 35 is another sprocket 40. Secured to a shaft 41 extending through the panel 21 is a sprocket 42 and secured to a shaft 43 likewise extending through the panel 21 is a sprocket 44. A sprocket chain 45 extends around the three sprocket gears 40, 42 and 44 and since the sprocket gear 40 is driven from the motor 22 at reduced speed the chain 45 is driven and drives the sprockets 42 and 44, the direction of drive being shown by the arrow in Figure 4. An idler sprocket 46 is mounted on a pin 47 in a bracket 15 20 48 having a slot 49 through which pass screws 50 (only one shown) extending into the panel 21 there being washers 51 on the screws 50 and by loosening and retightening the screws 50 the sprocket 46 can be adjusted to take out the slack in the chain 45.

25 Still referring to Figure 4, secured to the shaft 43 is a disc or block 55 which has a slideway 56 on the exposed face thereof. In this slideway 56 is a slide block 57 projecting from which is a pin 58. On the pin 58 is a link 59 the other end of which is on a pin 60 in the forked end of an arm 61 secured to a shaft 62. The slide block 57 can be adjusted in the slideway 56 by means of a screw 63 extending into a threaded hole in the block 57 and passing through a block 65 rigidly secured to the disc 55, the screw 63 having a bolt head 66 and a collar 67 for the purpose of turning it and preventing axial movement relative to the block 65. At the other end of the slideway 56 is another fixed block 68 through which extends a screw 69 to tighten the slide block 57 in any position to which it may be moved by the screw 63. In this manner, by first loosening the screw 69, then turning the screw 63, the pin 58 can be placed coaxial with the shaft 43 in which case the link 59 will not move at all, or at any radial distance from the axis of the shaft 43 up to the total permissive limit of movement as clearly shown in Figure 4, and after the adjustment is made, the block 57 can be locked in position by retightening the screw 69. This mechanism therefore causes oscillations of the shaft 62 responsive to rotation of the sprocket 44 and shaft 43, and the magnitude of the oscillations of the shaft 62 can be adjusted from zero to a

certain maximum amount by adjusting the position of the slide block 57 as described.

A wholly similar mechanism is provided to connect the rotating shaft 41 to oscillate a shaft 72 and it will be sufficient, in view of the above description, merely to identify the various parts. A disc or block 75 is secured to the shaft 41 and a disc or block 76 in which is a slide block 77 having a pin 78 on which is a link 79 connected to a pin 80 in the forked end of an arm 81 secured to the shaft 72. A screw, not shown, similar to the screw 63 extends through a block 85 and has a bolt head 86 and this screw is in threaded engagement with the block 77 and can be used to adjust the position of the block 77. Through a 15 fixed block 88 extends a locking screw 89.

Referring to Figures 4 and 5, supporting the shaft 62 is a bracket 95 which is fastened to the panel 21. The shaft 62 is journalled in this bracket 95 and also in the back wall 96 of a frame 97 for the encapsulating mechanism which, as shown in Figure 1, is secured to the panel 21 by means of screws 98.

On the shaft 62 and secured thereto is a gear 100 which meshes with a gear 101 secured to the outer ring 102 of an overrunning clutch 103 adapted to transmit motion in one direction only. The inner ring, not shown, of the overrunning clutch 103 is connected to a shaft 104 which is journalled in the back wall 96 and also in a bracket 105a secured to the front wall 105 of the frame 97 and this shaft 104 extends through the panel 21. Referring now to Figures 5 and 6, keyed to the shaft 104 by means of a key 106 is the inner ring 107 of an overrunning clutch 108 just like the overrunning clutch 103. The outer ring 109 of the overrunning clutch 108 has an extension 110 into a bore 111 in the bracket 105a. This extension 110 has a long bore therein receiving a sleeve 112 which forms the actual journal for the end of the shaft 104 which thereby, indirectly, is journalled in the bracket 105a. A key 113 in a keyway 114 backed up by a screw 115 holds the extension 110 and therefore the ring 109 from turning.

Between the outer ring 109 and the inner ring 107 are a plurality of sprags 116 which act just like pawls pivoted to one part and bearing against ratchet teeth in the other part except for the fact they lock the parts together in any position and therefore in an infinite number of relative positions instead of in a finite number of positions as in the case of a ratchet and pawl mechanism. Each of the sprags 116 is slotted at each end and extending through the slots are endless springs 117 which keep the sprags 116 in engagement with the surfaces.

The overrunning clutch 103 is the same as the overrunning clutch 108 so it is not necessary further to describe the details of clutch 103. The clutch 108 allows the shaft 104 to be turned in a counter-clockwise direction looking from the right of Figures 5 and 6 but prevents it from being turned in a clockwise direction. The gear 100 oscillates because of the oscillations of the shaft 62, and this causes the gear 101 to oscillate which oscillates the outer ring 102. Every oscillation in a counter-clockwise direction viewed from the right of Figure 5 drives the shaft 104 while the oscillations in the clockwise direction are non-driving oscillations. The pair of overrunning clutches 103 and 108 therefore function like driving pawls and holding pawls with ratchets. Retrograde movement of the shaft 104 is positively prevented while forward movement thereof is 75 100 prevented.

positively effected and due to the particular nature of these overrunning clutches there is no lost motion or backlash. It is believed to be unnecessary to give any fuller description of the overrunning clutches since they are now well known in the art and in fact are readily available on the market.

Referring now to Figure 4, secured to the shaft 12 which is suitably journalled in the back wall 96 is a gear 120 which meshes with a gear 121. Referring now to Figures 3 and 7, the gear 121 is secured to the outer ring 122 of an overrunning clutch 123 just like the clutches 103 and 108. The inner ring 124 of this overrunning clutch 123 is secured to a shaft 125 which is journalled in a bearing 126 in the back wall 96 and extends through the front wall 105 and a plate 128 fastened thereto. Secured to the shaft 125 is the inner ring 130 of an overrunning clutch 131, the same as the others already mentioned, having an outer ring 132 with an extension 133 extending through and secured to the plate 128. In this manner the shaft 125, the same as the shaft 104, is driven intermittently. I prefer to cause the shaft 125 to start moving about 45° before the shaft 104 starts to move, but this timing can be varied.

Referring now to Figures 5 and 6, mounted on and secured to the shaft 104 is a sleeve 135 having integral disc-like portions 136 which preferably have knurled or roughened peripheries. Secured to the shaft 104 is a gear 138 which meshes with a gear 139 secured to a shaft 140. The shaft 140 is journalled in the back wall 96 and also in the bracket 105a through which it extends. Mounted on and secured to the shaft 140 is a sleeve 145 having integral disc-like portions 146 also with knurled or roughened peripheries. These sleeves 135 and 145 with their integral disc-like portions 136 and 146 constitute feed rollers to feed gelatin ribbons 150 which are formed in a manner not necessary to be described herein. Each ribbon constitutes the material for one half of the casings of the multitudes of capsules which the machine produces. The filling material is pumped through pipes 151 which extend between successive disc-like portions 136 and 146 as shown in Figure 5 and these disc-like portions shape the ribbons 150 into tubes around the pipes 151, each ribbon 150 providing the material for one half of many tubes, for example five as indicated in Figure 5. The mechanism for pumping the filling material which is to go into the tubes forms no part of the present invention. On the front end of the shaft 140 may be affixed, removably if desired, a hand crank 153 by means of which the feed rollers can be turned in a forward direction at any time. By forward direction I mean to move the ribbons 150 downward. This is useful for setting up the machine, that it to say for threading it.

Referring now to Figure 1, journalled in the plate 128, which as shown therein is fastened by screws 155 to the front wall 105, is a bearing member 156 having a slot 157 through which extends a screw 158 into the plate 128 by means of which the bearing member 156 can be fastened in angularly adjustable positions. This adjustment is for the purpose of adjusting by a slight amount the position of a stop block portion 159 integral with the bearing member 156. Journalled in the bearing member 156 and concentric with it is a short cylindrical member 160. Rigidly secured to the short cylindrical

member 160 is a long shaft 161. Extending radially from the short cylindrical member 160 is a pin 162. The long shaft 161 is decidedly eccentric to the cylindrical member 160. By turning the member 160 with the pin 162, the axis of the shaft 161 can be moved through an arc. When the pin 162 is against the stop block portion 159, the parts are in operative position which is adjustable as described. When the pin 162 is moved upwards in a clockwise direction 10 the shaft 161 is moved away from the shaft 125. Referring to Figure 8, the rear end of the long shaft 161 is fastened to a short cylindrical member 165 which is axially aligned with the short cylindrical member 160 and is journaled 15 in the back wall 96. That is to say the bearing bore in the back wall 96 for the short cylindrical member 165 is aligned axially with the bearing bore in the member 166 which journals the member 160. The parts 160, 161 and 165 20 move as a unit but the shaft 161 is decidedly eccentric to the cylindrical members 160 and 165.

Secured to the shaft 125 is a take-up roller sleeve 167 preferably having a knurled surface. This sleeve is shown in full in Figure 7 and a portion of it is shown in Figure 3. Also secured to the shaft 125 as best shown in Figure 7 is a gear 168. This gear 168 is adapted to mesh with a gear 169 a fragment of which is shown in Figure 3 the gear 169 being secured to the take-up roller 170 also preferably having a knurled surface. A portion of this take-up roller 170 is visible in Figure 3. This take-up roller sleeve 170 is rotatably mounted on the shaft 161.

It will now be seen that by moving the pin 162 the roller 170 can be withdrawn from the roller 167 for threading the machine and when this is done the gears 168 and 169 simply unmesh. When the machine is threaded returning the pin 162 against the stop block portion 159 brings the rollers 167 and 170 close together again to grip the ribbons 150 now known as network because at this point the capsules have been formed and removed therefrom. Fine adjustment of the space between the rollers 167 and 170 can be made as above described. I will now describe the mechanism for removing the finished capsules which is more particularly the subject of the present invention.

Referring now to Figure 10, secured on the shaft 35 is a cam 180 which conveniently can be made in two parts 181 and 182 secured together by bolts 183, the part 181 being in this case approximately 180° of the cam being of one radius, and the part 182 having three lobes 184. These may, as shown, be about 60° apart.

Referring now to Figure 3, the frame 97 has side walls, the right-hand side wall 185 being shown in that figure. Secured to the outside of the side wall 185 are a pair of bearing brackets 186 through which passes a rock shaft 187. Secured to the ends of the rock shaft 187 are clamps 188 tightened by screws 189 to which are welded rods 190. The front rod 190 has thereon a block 191 which is secured in place by means of a screw 192. Referring now to Figures 3 and 10, a roller 193 is rotatably mounted on a stud 194 which extends through a portion of the block 191 and is secured thereto as by means of a nut 195. This roller 193 is a cam roller which is actuated by the lobes 184 of the cam 180 and therefore, during one revolution of the shaft 35, the front rod 190 is raised three times and allowed to fall after each rise and, by rea-

son of the connection of the rear rod 190 with the front rod 190 by way of the rock shaft 187, the rear rod 190 also rises three times and moves in synchronism with the front rod 190.

Referring now to Figures 3, 8 and 10, adjustably secured on the outer or left-hand ends of the rods 190 by means of set screws 200 are blocks 201. These blocks 201 have upstanding split portions 202 through bores in which extend set screws 203 which can be adjusted and then locked in place by clamping screws 204 extending through the split portions 202.

Slidably mounted on the front rod 190 is a long block 205 which has a long bore through which the rod 190 extends. This block 205 is urged to the left by means of a spring 206 on the rod 190 extending between the block 205 and the block 191, and normally an upstanding portion 207 of the block 205 abuts the set screw 203 in the upstanding portion 202 on the front rod 190, but Figure 10 shows the parts in open position with the upstanding portion 207 spaced from the set screw 203. The rear rod 190 passes through a short block 210 having an upstanding portion 211 to abut the screw 203 in the upstanding portion 202 on the rear rod 190, and the block 210 has horizontal play on the rod 190 rather than having a close sliding fit in the horizontal plane. A spring 212 on the rear rod 190 extends between the block 210 and a collar 213 and thus urges the block 210 to the left to cause the upstanding portion 211 to engage the set screw 203.

Referring now to Figures 3, 8 and 10, there is a downwardly extending slot 215 in each of the upstanding portions 207 and 211 and from the one to the other extends a taut wire 216 which is clamped in these slots 215 by screws 217 extending across the slots 215. This taut wire 216 is a stripper and is moved upwardly against the capsules 220 in the network 150 either to loosen them therein or to dislodge them.

I also provide strippers 221 each of which is made of sheet metal or other reasonably stiff sheet material and has a straight stripper edge 222 adapted to engage such capsules 220 as still remain in the network 150 and dislodge them therefrom, the remainder of these strippers 221 constituting deflecting portions 223 to guide the capsules away from the network 150 and to cause them to fall into suitable receivers 225 (see Figure 1). The left-hand stripper of the strippers 221 is welded to the underside of each block 201 which is cut at an angle as shown. The front of the right-hand stripper 221 is welded to the underside of the long block 205 and the rear of the right-hand stripper 221 is welded to the underside of the short block 210, these blocks 205 and 210 being also cut at an angle as shown.

I further provide mechanism for moving the right-hand stripper 221 from the position shown in Figure 8 to the position shown in Figure 10 to facilitate the threading of the machine. This mechanism is illustrated in Figures 7, 8, 9 and 10. As shown in Figure 7, a horizontal shaft 230 is journaled in the back wall 96 and in the front wall 105 and extends between them. Clamped to the shaft 230 which extends through it is a gooseneck arm 231 which has a slot 232 across which extends a screw 233 to effect the clamping. The gooseneck arm 231 has an upper forked end 234 which straddles the front rod 190 and can be brought to bear against the left-hand end of the long block 205, Figures 8 and 9. The gooseneck arm 231 has, as shown in Figure 10, an integral extension 235 to the right having a boss

236 through which extends a screw stud 237 secured in place with a nut 238, the stud 237 acting as an adjustable stop by engagement with the underside of the front wall 105 to hold the gooseneck arm 231 in inactive position against the action of a spring 239 secured in a hole 240 located in a recess 241 in the underside of the long block 205 and also secured in a hole 242 in a recess 243 in the upper side of the extension 235.

As shown in Figure 9, the outer and upper end of the extension 235 has a pin 245 extending horizontally therefrom which is engaged by an eccentric 246 having a hub 247 secured to a short shaft 248 extending through end journalled in the front wall 105, the pin 245 being engaged by the eccentric 246 whenever a knurled knob 249 is turned to the right, Figure 1. A stop pin 250 extending from the eccentric 246 engages the pin 245 when it reaches the position shown in Figure 10 in which position the eccentric 246 has forced the pin 245 downwardly to rock the gooseneck arm 231 to its extreme limit in a clockwise direction whereby the upper forked end 234 has forced the long block 205 to the right on the front rod 190. When the knurled knob 249 is turned to the left, Figure 1, the stop pin 250 is moved back until it engages a fixed pin 251 extending rearwardly from the front wall 105 and thereupon, the eccentric 246 having moved well away from the pin 245, the spring 239 moves the gooseneck arm 231 in a counter-clockwise direction thus allowing the spring 206 to reposition the long block 205.

Referring now to Figure 8, secured to the horizontal shaft 230 near the back wall 96 is another gooseneck arm 255 being in shape like the gooseneck arm 231 only it has no integral extension 235. This gooseneck arm 255 through which the shaft 230 extends has a slot 256 across which a screw 257 extends to effect the clamping action. This gooseneck arm 255 likewise has an upper forked end 258 straddling the rear rod 190 and adapted to engage the left-hand end of the block 210. It will readily be seen that whenever the gooseneck arm 231 is moved, the gooseneck arm 255 must likewise move, and thus whenever the block 205 is moved to the right on its rod 190, the block 210 must likewise move, and so therefore by turning the knurled knob 249 to the right, the stripper wire 216 and the right-hand stripper 221 are moved away from the left-hand stripper 221 thus to permit threading of the machine, and thereafter, by turning the knurled knob 249 to the left, the stripper wire 216 and the right-hand stripper 221 are returned to operative position.

The block 205 has a bevel or cam portion 260 which, when the knurled knob 249 is turned to the right, engages the fixed pin 251 thereby lifting the rods 190 thus raising the taut wire 216 and the additional strippers 221 and carrying the roller 193 just clear of the cam lobes 184 so that, when the stripper mechanism is thus opened up for threading the machine, the strippers are motionless.

In the cycle of operation, when the take-up rollers 167 and 170 stop, the strippers are up. Immediately thereafter they move downwardly as the last lobe 184 passes beyond the roller 193. When the take-up rollers stop, the encapsulating mechanism not shown or described herein operates to form the capsules 220 and during operation of the encapsulating mechanism the strippers are down. About 35° before the completion of the operation of the encapsulating mechanism at the end of which operation the

capsules 220 are cut from the network 150, the take-up rollers 167 and 170 start moving. Forty-five degrees after the start of the take-up rollers, which is 10° after the encapsulating and severing, the feed rollers 135 and 145 with their integral disc-like portions 136 and 146 start moving. Thirty degrees after the take-up rollers start moving which is 10° before the feed rollers start moving, the strippers start to move upwardly by engagement of the first lobe 184 with the roller 193. Thus it will be seen that the three rising and falling motions of the strippers including the taut wire 216 are accomplished for the most part while the take-up rollers and the feed rollers are moving. Thus as the strippers rise the network 150 is moving downwardly and this materially helps to dislodge the capsules 220. In the above description the reference to degrees of movement is based upon the rotation of the shaft 35; thus one complete rotation of the shaft 35 represents 360°. The gear ratios of the gearing hereinbefore described is selected so that the take-up rollers move about one-third to one-half further during each cycle of operation than do the feed rollers. This ratio can be varied as desired by adjustment of the screw 63 and the screw not shown having the bolt head 86. It is advantageous to cause the take-up rollers to move farther than the feed rollers as this stretches the network during encapsulation and facilitates the formation of the capsules. The take-up rollers 167 and 170 are for this reason frequently referred to as tension rollers.

It is particularly advantageous to time the stripping mechanism to operate only when the encapsulating mechanism is not acting upon the ribbons or network. Otherwise, the contact of the strippers with the capsules disturbs the tension of the network which can result in the production of off-size capsules or misshaped capsules. The action of the encapsulating mechanism is synchronized to the feeding and taking up of the ribbons and network and therefore by timing the stripping to feeding and taking up I have effectually avoided disturbance of the network during encapsulation. Furthermore there are positive advantages in operating the stripping mechanism when the take-up rollers and the feed rollers are operating, for it is at this time that the network is moving downwardly and therefore the relative movement between capsules and strippers is both greater and faster than if the strippers moved while the network was stationary. The mechanism of this invention has been found to be quite effective in removing capsules from the network and furthermore the adjustments provided enable it to be set for different sizes and shapes of capsules. The particular timing above described may, however, be widely varied and I am not to be limited to relative timing of the motions and mechanisms more strictly than as called for by the following claims.

It will be seen that the strippers 221 are adjustable relative to the network 150, that is to change the width of the gap between them, and they should preferably be adjusted so that this gap will be less than the dimension of the capsules 220 normal to the network 150. In this manner contact between the strippers and the capsules is ensured.

It will thus be seen that there has been provided by this invention a feed, take-up and stripper mechanism for encapsulating machines in which the various objects hereinabove set forth together with many thoroughly practical advan-

tages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In an encapsulating mechanism, a pair of strippers one on either side of a network from which capsules were formed, intermittently operating driving mechanism to move said strippers to and fro in directions with and counter to the movement of said network, pairs of feeding and take-up rollers to move said network past said strippers, intermittently operating driving mechanism for said feeding and take-up rollers respectively, a main drive for all of said intermittent driving mechanisms, and a driving connection from the main drive to each of the intermittent driving mechanisms of one to one positive driving ratio and so set that the strippers move counter to the movement of the network only when at least one of said pairs of rollers is moving.

2. Apparatus as claimed in claim 1 in which a taut wire parallel to one of the strippers is connected to one of the pair of strippers to move to and fro with it.

3. A stripper mechanism for encapsulating machines comprising a pair of parallel rods, a rock shaft connecting said rods, mechanism to oscillate said rods up and down on the axis of said rock shaft, said rods being at some moment during the oscillation substantially perpendicular to network from which capsules were formed, and a pair of strippers adjustably carried by said rods one on either side of said network said strippers having straight stripper edges and deflecting portions connected thereto.

4. A stripper mechanism for encapsulating machines as claimed in claim 3 having additionally a taut wire parallel to the straight stripper edges and located on one side of the network close thereto.

5. A stripper mechanism for encapsulating machines comprising a pair of parallel rods, a rock shaft connecting said rods, mechanism to oscillate said rods up and down on the axis of said rock shaft said rods being at some moment during the oscillation substantially perpendicular to network from which capsules were formed, a pair of fixed blocks secured to said rods one on each, a pair of slidable blocks on said rods one on each, spring means urging said slidable blocks towards said fixed blocks, adjustable stop means to adjust the position of the slidable blocks relative to the fixed blocks, a stripper connecting the pair of fixed blocks and secured to them said stripper being on one side of the network, and a stripper connecting the pair of slidable blocks and secured to them said stripper being on the other side of the network.

6. A stripper mechanism for encapsulating machines as claimed in claim 5 having additionally manually operable means for moving the slidable blocks away from the fixed blocks and holding them in removed position whereby to facilitate threading of the machine.

7. A stripper mechanism for encapsulating

machines as claimed in claim 6 having additionally means to hold the strippers stationary in a given position when the slidable blocks are moved away from the fixed blocks.

8. In an encapsulating machine, a pair of feed rollers, a pair of take-up rollers, intermittent driving mechanism to move said pairs of rollers in synchronized relationship so that for at least a portion of a cycle of machine operation they will be simultaneously moving and in such directions that ribbons and network between them will be moved in a given direction, said pairs of rollers being parallel and spaced close to each other to grip and thereby feed said ribbons and network, a pair of strippers each having a straight edge, a mounting for each stripper holding the straight edge thereof close to and parallel to the plane of the network, said straight edges being separated from each other in the mid-position of each by a distance less than the thickness of a capsule, said mountings allowing each straight edge of each stripper to move in the given direction and in opposition thereto, and power means to move said straight edges in the given direction and in opposition thereto synchronously to the intermittent driving mechanism to move them in opposition to the aforesaid given direction only when both pairs of rollers are moving and never moving said straight edges in opposition to the given direction when both said pairs of rollers are stationary.

9. In apparatus as claimed in claim 8, the combination with the parts and features therein specified of the further feature that the strippers have deflecting portions having plane surfaces making obtuse dihedral angles to the feeding side of the plane of the network.

10. In apparatus as claimed in claim 8, the combination with the parts and features therein specified of the further feature that the strippers are moved simultaneously and at the same rate.

11. In apparatus as claimed in claim 8, the combination with the parts and features therein specified of a taut wire constituting a stripper in addition to the pair of strippers and positioned parallel to the straight edges and connected to one of the pair of strippers to move with it.

12. In a stripping mechanism for an encapsulating machine having a cycle of operation, a pair of strippers one on each side of the network, means to reciprocate the strippers up and down during a portion of one cycle and to hold them inoperative during the remainder of the cycle and means to move the network intermittently, said network being held stationary at intervals and moved downwardly at intervals and said network being moved downwardly while the strippers are reciprocating.

CHARLES C. ALVORD.
